CLAIM

The ornamental design for a closure for a bottle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first perspective view of a first embodiment of a closure for a bottle;

FIG. 2 is a front view of the closure for a bottle of FIG. 1;
FIG. 3 is a first side view of the closure for a bottle of FIG. 1;

FIG. 4 is a back view of the closure for a bottle of FIG. 1;
FIG. 5 is a second side view of the closure for a bottle of FIG. 1;

FIG. 6 is a top view of the closure for a bottle of FIG. 1;
FIG. 7 is a bottom view of the closure for a bottle of FIG. 1;

FIG. 8 is a perspective view of a second embodiment of a closure for a bottle;

FIG. 9 is front view of the closure for a bottle of FIG. 8;
FIG. 10 is first side view of the closure for a bottle of FIG. 8;

FIG. 11 is a back view of the closure for a bottle of FIG. 8;
(Continued)

FIG. 12 is a second side view of the closure for a bottle of FIG. 8;

FIG. 13 is a top view of the closure for a bottle of FIG. 8; and,

FIG. 14 is a bottom view of the closure for a bottle of FIG. 8.

The broken lines shown in the drawings are for environmental structure or boundaries that form no part of the design to be patented.
